UNITED STATES PATENT OFFICE.

GEORGE W. EDWARDS, OF DETROIT, MICHIGAN, ASSIGNOR OF ONE-HALF TO WILLIAM J. JOLIVETTE, OF DETROIT, MICHIGAN.

STEAM-BOILER.

1,183,961.

Specification of Letters Patent. Patented May 23, 1916.

Application filed July 17, 1915. Serial No. 40,361.

To all whom it may concern:

Be it known that I, GEORGE W. EDWARDS, a citizen of the United States of America, residing at Detroit, in the county of Wayne 5 and State of Michigan, have invented certain new and useful Improvements in Steam-Boilers, of which the following is a specification, reference being had therein to the accompanying drawings.

10 This invention relates to steam boilers, and it has for one of its objects the provision of means whereby the circulation of the water in the boiler will be enhanced.

A further object of the invention resides 15 in the provision of improved means whereby the circulation of the water in the boiler will project all heavy and impure matter into the bottom of the boiler, where a pipe connected to a blow-off cock can readily discharge the same therefrom.

Further objects of the invention will hereinafter appear and be particularly defined in the claims.

The invention has been clearly illustrated 20 in the accompanying drawings, in which similar characters denote similar parts, and in which:

Figure 1 is a cross-section of a boiler of the marine or Scotch type; Fig. 2 represents 25 a fractional longitudinal section of the boiler, showing portions of the plates and the deflecting gates thereof, this view being taken on or about the line II--II of Fig. 1; Fig. 3 is a detail sectional view of a plate 30 connection, and Fig. 4 is a cross section for a baffle member for a boiler having two main flues.

Referring to the drawings, 10 denotes the 35 boiler shell through which pass three main flues 11, which may be of any desired construction, while the small tubes are indicated by 12. In the present instance I provide within the boiler shell a pair of circulating plates 13 disposed at opposite sides 40 of the central line of the boiler and extending upward to a point substantially on line with the uppermost row of small tubes 12, while at their lower edges they are spaced to permit the circulation of water, as follows: It is evident that the water in direct 45 contact with the flues 11 and 12 will be hotter than the water which is in contact with any part of the outer boiler shell. Actual 50 experience has demonstrated the fact that 55 when circulating plates are provided in the

manner illustrated, the hot water on the inside of the circulating plates will, by virtue of the ebullition thereof, rise or move upward, so that consequently the body of water contained between the circulating 60 plates 13 and the outer shell will move downward or in the direction of arrow a. Now it sometimes happens that the circulation thus established is somewhat stronger on one side of the boiler than it is on the other, and it 65

is also shown that the two circulations thus established may have a tendency of counteracting each other or to form a check which may even result in forcing the downwardly moving water on one side of the 70 boiler slightly backward.

In order to avoid this difficulty and to equalize, as far as possible, these counteracting strains or movements, I provide in the bottom of the shell, and in the space between the lower edges of 75

the circulating plates, baffle members 14 preferably U-shaped in cross section, the open sides of said members being toward the right and left and are so arranged as to intercept the downwardly moving streams, 80 so that consequently they will be directed in an upward direction indicated by arrows b.

The upper terminals of the baffle members are in proximity to the central main flue 11 and the lower terminals 14' of said 85 members adjacent the boiler shell 10, thus forming pockets that retard and deflect the circulation of water. It is essential however, that the lower terminals 14' of the baffles be slightly spaced from the boiler shell, in order to permit all heavy matters 90

or impurities to pass beneath the same into what may be termed the "sediment chamber" established beneath the baffles and also containing a pipe 15 which is preferably 95 perforated and extends through the boiler head at which point a blow-off cock (not shown) may be provided, which, when opened will permit all sediment collected to be blown out, as will be readily understood. 100

It has been stated above that my present invention comprises as one of its features, certain novel means for forming and connecting the members or parts of the circulating plates, and by referring to Figs. 1 and 2, it will be seen that each circulating member consists of a series of plates c, the horizontal edges of which abut each other while their vertical edges are guided or held in grooved holders 16, 17, the holders 16 being 105 110

secured to the boiler heads and consisting preferably of three members r, r', r'' , which are riveted together in the manner shown, the middle member r' being less in width than the other two members so as to form a groove. The holders thus formed may be held in position by brackets 20 disposed at various points along the plate, as shown. Furthermore, brace members or brackets, such as indicated at 21 are used in conjunction with the plates and interposed between the circulating members and the boiler shell. The several plates c of the boiler are made in sections indicated in a general way by A and B in Fig. 2, the two sections being supported at their adjacent edges by an intermediate grooved holder 17 formed in a similar manner to the outer holders above described and consisting preferably of the three members i, i', i'' , the intermediate one being less in width than the outer ones and thus forming at the opposite sides thereof a pair of grooves which are adapted to receive the marginal portions of the plates c , it being understood that the three members of the intermediate holder 17 are riveted together. Brackets similar to the brackets 20 above described are used in conjunction with this intermediate holder.

Means are provided whereby the central portions of the several plates c will be retained in contact, or in other words, whereby their adjacent edges will be held together and in alignment with each other vertically, these means consisting preferably of strips 25 (see Fig. 3) riveted to the upper edge of one plate c and forming a groove adapted to receive the lower edge of the next adjacent plate. By virtue of this construction it will be readily understood that the several plates c can be readily inserted into place because they are formed in comparatively short sections of such width as may be readily passed through the man-hole of the boiler.

The lower ends of the circulating plates 13 terminate in deflecting gates 30, each made of longitudinal sections having the edges thereof connected, as at 31. The lower ends of the deflecting gates 30 are trunnioned or pivoted, as at 33, in the end walls 32 of the boiler shell 10 and the upper edges of said gates are in proximity to the stationary portions of the circulating plates 13 and at the lower ends of the holders 16 and 17. These holders terminate at the lower edges of the stationary portions of the walls to provide clearance for adjustment of the gates 30; and provision is made whereby each gate can be adjusted to restrict the passage between the gate and the boiler shell to deflect a portion of the outer body of water, in the passage, into the inner body of water. The means employed for this purpose, consist of rock shafts 34 journaled in

the end walls 32 of the boiler shell 10. An end of each shaft has a crank 35 or suitable device to facilitate rocking the shaft and said shaft, within the boiler shell, extends through bearings 36 at the lower edge of the stationary portion of each circulating plate 13. The shaft, at each bearing, has a crank 37 pivotally connected by a link 38 to the upper edge of the gate, consequently by rocking the shaft, the gate can be opened or adjusted, as shown by dotted lines at the right hand side of Fig. 1.

In Fig. 4 there is shown a baffle member 39, of inverted V-shape in cross section, which can be used with circulating plates in a boiler having a pair of main flues.

I claim:—

1. The combination with a boiler shell, and the flues thereof, of a pair of circulating plates spaced from said shell, baffle members 85 at the bottom of said shell, and adjustable deflecting gates trunnioned contiguous to said baffle members and adapted to have the free edges thereof moved relative to the lower ends of said circulating plate. 90

2. The combination with a boiler shell, and the flues thereof, of a pair of circulating plates surrounding said flues and spaced from said shell, deflecting gates trunnioned in the lower part of said shell as a continuation of said circulating plate, and means carried by the lower edges of said circulating plate adapted to move the free edges of said deflecting gate to and from the lower edges of said circulating plate. 95

3. In a boiler, circulating plates, deflecting gates trunnioned in said boiler as a continuation of said circulating plates and having edges thereof adjustable at the edges of said circulating plate, said circulating plate 105 and said gates being composed of plates having abutting edges, and strips carried by an edge of each plate providing a groove to receive the edge of an adjoining plate.

4. In a boiler, circulating plates, deflecting gates trunnioned in said boiler adjacent to the lower edges of said circulating plates and having the free edges thereof at the edges of said circulating plate, and means including a rock shaft supported by the 110 edges of said circulating plates adapted to adjust the free edges of said deflecting gates.

5. The combination with a boiler shell and the flues thereof, of a pair of circulating members interposed between flues and the 120 shell and spaced from each other at their lower edges, each member comprising a plurality of plates having their adjacent edges abutting each other, means for holding said edges together, means for holding the end 125 edges of said plates in position in the shell, and adjustable deflecting gates at the lower edges of said members having the upper edges thereof disposed to swing toward said boiler shell. 130

6. The combination with a boiler shell and the flues thereof, of a pair of circulating members interposed between flues and the shell and spaced from each other at 5 their lower edges, each member comprising a plurality of plates having their adjacent edges abutting each other, means for holding said edges together, grooved members secured to the boiler heads for holding the 10 end edges of said plates in position in the shell, adjustable gates supported by the lower edges of said circulating members and the end walls of said boiler shell, and means including rock shafts for adjusting said 15 gates.

7. The combination with a boiler shell, and flues, of a circulating plate disposed between said flues and the boiler shell providing a water passage, and means normally as a continuation of said plate adapted to be 20 swung toward said shell to deflect water from said passage toward said flues at a point intermediate the ends of said passage.

In testimony whereof I affix my signature in presence of two witnesses.

GEORGE W. EDWARDS.
